ELIZABETH R. ROYCE, OF CAMBRIDGE, MASSACHUSETTS.

INFANT'S UNDERGARMENT.

1,110,459.

Specification of Letters Patent. Patented Sept. 15, 1914.

Application filed April 9, 1914. Serial No. 838,637.

To all whom it may concern:

Be it known that I, ELIZABETH R. ROYCE, a citizen of the United States, and a resident of Cambridge, in the county of Middlesex, State of Massachusetts, have invented a certain new and useful Improvement in Infants' Undergarments, of which the following is a full, clear, and exact description.

My invention relates to undergarments and particularly to what are known as infants' "bands." These garments as ordinarily made are of knitted material and are provided front and back with tabs projecting therebelow to which a diaper or other nether garment may be attached by means of pins. As now made these tabs are slightly reinforced to prevent tearing by the pins but the strains put upon the knitted fabric thereabove, especially as soon as the child begins to kick, creep and walk, result in the garment being quickly torn and the life of the garment is not nearly as long as it should be.

The object of my invention is the provision of a garment which shall be so made as to be reinforced to take up the strains imposed on the portions above the tab and which will at the same time yield to accommodate the band to the movements of the wearer. According to my invention this result is accomplished by providing a reinforcing strip extending from the bottom of the tab to or near the top of the garment and so constructing the strip that, while of stronger material than the remainder of the garment (which latter is usually of wool) it will yield to a considerable strain and will distribute such strain substantially throughout the height of the garment—instead of concentrating it just above the tab as in the present article. This can be most conveniently accomplished in the manner shown in the accompanying single sheet of drawings in which—

Figure 1 is a perspective view of a garment embodying one form of my invention; and Fig. 2 is a cross section, on a much larger scale, of a portion of the garment shown in Fig. 1.

In the drawings A indicates a garment of the type known as an infant's band, provided front and rear with tabs 5 and 7 to which other garments may be attached by pinning. This garment is made of knitted material, preferably wool though I do not limit myself to that material, and is pro-

vided with a reinforcing strip S of woven material extending from the bottom of the tab to the top of the garment. This reinforcing strip is sewed along its edges 1 and 2 to the garment A and is attached "full" when the garment is in an unstretched condition, as indicated in Fig. 1. Being of woven material, as opposed to knitted of which the remainder of the garment is made, the strip S is relatively unstretching and so, when a strain is placed upon the strip, the fullness will be taken up gradually from the bottom toward the top. On account of the unstretching character of the strip it will communicate to the portion of the knitted fabric adjacent any particular part only the proper proportion of the strain placed upon the strip—that is to say up to the point where the entire strip becomes taut—and any additional strain placed upon the strip will be communicated to a point farther up. Tearing of the knitted fabric of the garment due to the movements of the child wearing it will therefore be effectually avoided.

I am aware that it has been proposed heretofore to strengthen woven material garments by the addition of woven material reinforcing strips along the lines of greatest strains. However, as both these materials are unyielding, the result obtained by the addition of the reinforcing strip is merely to make this unyielding character more certain. Garments constructed in such a manner are not suited to the purpose to which infants' bands or the like are to be put. This is for the reason both that these materials are by nature unsuited to use as infants' undergarments on account of their texture but also because these garments should stretch to a certain degree and so afford the child wearing them freedom of movement. It is therefore essential, according to my invention, that the reinforcing strip employed, while calculated to distribute the strain throughout the garment, should also be of a yielding character.

While I have described my invention in connection with an infant's band, in which embodiment I consider it to be the most useful, I do not wish to limit myself to that particular garment but I may apply it to any garment of a yielding character which it may be desired to reinforce due to strains being applied to it at some particular point or points.

Having thus described my invention, what

I claim and desire to secure by Letters Patent is:

1. A garment comprising a knitted body portion, means to which another garment 5 may be secured, and a reinforcing strip of woven material extending from said securing means a substantial distance across said garment, said strip being attached "full" when the garment is in an unstretched condition.
- 10 2. A garment comprising a knitted body portion, a tab projecting therebelow, and a reinforcing strip of woven material extending from said tab substantially to the top of the garment, said strip being attached 15 "full" when the garment is in an unstretched condition.

3. A garment comprising a knitted body portion, a tab projecting therebelow, and a reinforcing strip of woven material extending from the tab substantially to the top 20 of the garment, said strip being so secured to the garment as to be "full" when the knitted portion is unstretched and to be taut when said knitted portion is stretched.

In testimony whereof, I have hereunto affixed my signature in the presence of two witnesses.

ELIZABETH R. ROYCE.
